(57) **CLAIM**

The ornamental design for a storage container, as shown and described.

DESCRIPTION

FIG. 1 is a top perspective view of a storage container showing our new design;

FIG. 2 is an exploded right view thereof;

FIG. 3 is an exploded left view thereof;

FIG. 4 is an exploded front view thereof;

FIG. 5 is an exploded rear view thereof;

FIG. 6 is a top plan view thereof;

FIG. 7 is a bottom plan view thereof;

FIG. 8 is a top perspective view thereof;

FIG. 9 is a top perspective view with lid thereof;

FIG. 10 is a top perspective view of an alternative embodiment of FIG. 1;

FIG. 11 is an exploded right view of FIG. 10;

FIG. 12 is an exploded left view of FIG. 10;

FIG. 13 is an exploded front view of FIG. 10;

FIG. 14 is an exploded rear view of FIG. 10;

FIG. 15 is a top plan view of FIG. 10;

FIG. 16 is a bottom plan view of FIG. 10; and,

FIG. 17 is a top perspective view of FIG. 10.

The container is shown without the lid for convenience of illustration only. The broken lines illustrate unclaimed portions of the design and environment and form no part of the claimed design.

1 Claim, 14 Drawing Sheets
